UNITED STATES PATENT OFFICE.

JULIUS PANKRATZ, OF RICHMOND HILL, NEW YORK.

DESIGN FOR A CHANDELIER.

Application filed January 17, 1921. Serial No. 438,022. Term of patent 7 years.

To all whom it may concern:

Be it known that I, JULIUS PANKRATZ, a citizen of the Republic of Hungary, residing at Richmond Hill, county of Queens, and State of New York, have invented a new, original, and ornamental Design for a Chandelier, of which the following is a specification, reference being had to the accompanying drawing, forming part hereof.

Fig. 1 is a side elevation of a chandelier with a portion broken away, and Fig. 2 is an inverted plan view of one half of the same.

I claim:

The ornamental design for a chandelier, as shown.

JULIUS PANKRATZ.
